STRAPPED MAGNETRON

Albert M. Clegston, Melrose, Mass., assignor, by
mesne assignments, to the United States of
America as represented by the Secretary of War

Application March 1, 1946, Serial No. 651,302

4 Claims. (Cl. 315—40)

1

This invention relates to electron discharge devices and particularly to an improved method of strapping magnetrons.

The conventional magnetron structure includes a number of chambers, or resonant cavities, symmetrically disposed within the anode ring. A number of modes of oscillation are possible, usually being one less than the number of cavities present. It is desirable, however, that oscillation be restricted to as few widely separated modes as possible, so that all the output power may be concentrated in the frequency range due to this mode, and the tuning may be as sharp as possible.

This aim is achieved by "strapping," or connecting certain of the resonant cavities together. Conventionally, the strapping takes the form of annular members disposed concentrically with the anode ring and connecting alternate anode segments together. The anode segments are those portions of the anode structure extending radially inward from the anode ring to constitute the walls of the resonant cavities.

These annular members are disposed as near to the inner circumference of the anode structure as is convenient, and may be on one or both ends of the anode.

The most effective results are obtained when the impedance path presented by the strapping rings is a minimum. For this reason the straps are commonly made as heavy as possible relative to the rest of the structure; usually two rings are concentrically disposed on the same end of the anode, each ring being brazed to alternate anode segments, and such double strapping is duplicated at the opposite end of the anode.

The location of two concentric rings close together tends to increase the capacitance of the system, with consequent reduction of the impedance, but is limited by the spacing which must be maintained to avoid flashovers.

The present invention contemplates heavier strapping, hence greater mode separation, with a system having substantially the same dimensions as the conventional double ring strapping, by using an inner ring almost completely enclosed by an outer strap. This reduces the impedance by lowering the inductance instead of by increasing the capacitance.

The invention may be better understood by reference to the drawing, in which:

Fig. 1 represents a double strapped magnetron anode;

Fig. 2 is a fragmentary view partially in sec-

2

tion taken diametrically across a magnetron formed in accordance with this invention;

Fig. 3 is a fragmentary cross-sectional view of the improved strapping arrangement, taken as indicated by line 3—3 of Fig. 2; and

Fig. 4 is a fragmentary cross-sectional view of the improved strapping arrangement, taken as indicated by line 4—4 of Fig. 2.

Referring now to Fig. 1 of the drawing, 1 indicates a magnetron anode having a plurality of radially disposed vanes alternately designated by the numerals 2 and 4, between which are resonant cavities 5. An annular strap 6 is disposed adjacent the inner ends of the vanes, and secured, as by brazing, to those numbered 2. A second annular strap 7 is disposed concentrically within strap 6, and is secured to the alternate vanes 4. The alternate vanes 4 are cut away at 9 so that there will be no contact with the annular strap 6, while vanes 2 are similarly cut away at 10 to clear strap 7.

Between straps 6 and 7 capacitance is added to the circuit, which reduces the impedance and promotes mode separation. To make the increase in capacitance a maximum, these straps must be made as deep as possible, and located as closely together as is permissible in view of the voltages involved. The practical limitations on these two factors substantially define the mode separation obtainable by such means.

In Figs. 2, 3 and 4 is illustrated a preferred version of this invention. An outer or tunnel shaped strap 15 is set into snugly fitting recesses 16 in alternate vanes 18. Intermediate alternate vanes 19 are recessed at 20 to provide adequate clearance for strap 15. A second tunnel shaped strap 11 is set in recesses 14 in alternate vanes 19, intermediate vanes 18 being recessed at 17 to provide clearance for strap 11. Concentrically within the tunnel strap 15 is disposed a conventional ring strap 21 arranged to be connected to each of the intermediate alternate vanes 19, but spaced from the alternate vanes 18. A similar strap 13 is connected to vanes 18 but spaced from vanes 19. At each juncture of vanes and ring or tunnel straps, a firm connection is made by the usual means such as brazing or "sweating in" a silver solder.

It will be observed in the drawing that opposite connections of vanes and straps are used at the opposite ends of the anode structure. For example, as seen in Fig. 4, whereas the upper end of alternate vane 18 is connected to tunnel shaped strap 15, the lower end is connected to ring strap 13. Likewise, as seen in Fig. 3, where

the upper end of intermediate alternate vane 19 is connected to inner or ring strap 21, the lower end is joined to tunnel shaped strap 11. It will be obvious to those skilled in the art that the strapping may be restricted to one end if desired.

The effect of the arrangement of this invention is to reduce the inductance of the strapping system, while maintaining the same separation between the straps and substantially the same strap depth. Hence the impedance is reduced and the mode separation may be increased beyond that possible with the double strapping system of the prior art.

What is claimed is:

1. A magnetron anode comprising a plurality of radially disposed cavity resonators separated by conducting walls, an annular member having a tunnel-shaped cross-section throughout its entire length and connected at one end of said resonators to alternate ones of said conducting walls near the inner ends thereof, and a second annular member symmetrically disposed throughout its entire length within said tunnel-shaped member and connected to those of said conducting walls not joined to said tunnel-shaped member.

2. A magnetron anode having a plurality of cavity resonators separated by dividing walls, means comprising an annular conductor having a tunnel-shaped cross-section throughout its entire length and disposed adjacent the inner peripheral boundary of said resonators and connected to alternate dividing walls thereof, and an annular strap disposed throughout its entire

length within said tunnel-like conductor and joined to those of said dividing walls not connected to said tunnel-like conductor.

3. A magnetron anode having a plurality of cavity resonators separated by conducting walls, an inner strapping conductor joined to alternate ones of said conducting walls, and an outer strapping conductor enclosing said inner conductor throughout its entire length, and joined to those of said conducting walls not engaged by said inner conductor.

4. A magnetron anode as set forth in claim 3, wherein said conductors are positioned in the upper portion of said walls, and further including a second inner strapping conductor, and a second outer strapping conductor enclosing said second inner conductor throughout its entire length, said second outer conductor being joined to the same walls as said first mentioned inner conductor, and said second inner conductor being joined to the same walls as said first mentioned outer conductor, said second conductors being positioned in the lower portion of said walls.
